CORE-CATCHING DEVICE

Application filed June 5, 1929. Serial No. 368,595.

My invention relates to a novel form of core barrel in which is incorporated a novel core-catching device which is automatically operated when the core barrel is raised.

In taking core samples of the strata through which a well is being drilled, it is customary to lower a core barrel, the core sample rising in a core chamber thereof and being therein entrapped to prevent an escape thereof during the raising of the core barrel. This entrapping is usually accomplished by spring fingers resiliently extending into the core chamber and being deformed outward by the passage therethrough of the core.

It is an object of this invention to provide a core-catching device which is positive in its gripping action.

Another object of this invention lies in the provision of a novel core-catching device operable at a remote point to exert a positive gripping action on the core when the core barrel is first raised.

Still another object of the invention is to provide a core barrel having two elements movable relative to each other over a limited distance, this relative movement being used in clamping the core in the core chamber.

Still other objects of the invention lie in the novel construction of the parts wherein the weight of one of the elements of the core barrel is effective in exerting a gripping force on the core.

Further objects and advantages of the invention will be evident to those skilled in the art from the following description.

In the drawings, I have illustrated one form of the invention, but it should be understood that I am not limited to this form to the exclusion of other similar forms capable of performing the desirable results made possible by my invention.

Fig. 1 is a utility view illustrating the way in which my core catcher is used.

Fig. 2 is a vertical sectional view through the core catcher.

Fig. 3 is a horizontal sectional view taken on the line 3-3 of Fig. 2.

Fig. 4 is an enlarged sectional view of the core-catching device.

Figs. 5 and 6 are cross-sectional views taken as shown by their respective lines of Fig. 4.

Fig. 7 is a perspective view of one of the jaws of my invention.

Referring particularly to Fig. 1, I have illustrated a string of drill pipe 10 extending downward in a well 11 and being rotated by a rotary machine 12, the lower end of this drill pipe being secured to a core barrel 15 incorporating the features of my invention.

The details of the core barrel 15 of my invention are best shown in Figs. 2 and 6. Referring particularly to Fig. 2, a tool joint 20 is secured to the lower end of the string of drill pipe 10 and provides a threaded cavity 21 which receives the upper end of a supporting member 22. This member is formed of tubular material and provides a head 23 at the lower end thereof, a hole 24 being formed therethrough which communicates with the interior of the supporting member 22.

Formed on the exterior of the head 23 is a pair of pockets 25 which are sector-shaped in horizontal cross-section, as best shown in Fig. 3. Adapted to vertically slide in each pocket is a guide block 27 formed integrally with, or suitably attached to, an outer tubular member 30 which surrounds the head 23, these guide blocks being vertically slideable a distance determined by the difference in length of the guide blocks 27 and pockets 25. This movement is usually in the neighborhood of two inches.

The outer tubular member 30 extends downward a considerable distance from the head 23 and the lower end thereof is externally threaded to receive a core-catching body 32 providing a bore 33 therethrough. The outer tubular member 30 and the body 32 co-operate in forming an outer barrel 35 of my invention.

Clamped in the threaded cavity 21 between the supporting member and a shoulder of the tool joint is a spider 36, a central boss 37 of which is drilled to receive a threaded adjusting member 38, this member having a nut 39 which adjusts the vertical position of the member 38 relative to the spider. Carried by the lower end of the adjusting mem-

ber 38 is a cage 40 of a check valve 41 of any desired construction which will prevent the passage of any fluid therethrough and into an inner tubular member 43 suspended therefrom through a cap 44, this check valve readily permitting an upward flow of fluid from the inner tubular member 43.

This tubular member is formed to loosely slid in the hole 24 of the head 23 and extends 10 downward therethrough to a point inside the body 32. Here a sleeve 45 is threaded thereto, this sleeve having an external diameter only slightly smaller than the diameter of the bore 33 so as to be slidable therein when 15 a relative movement between the outer member 30 and an inner barrel 46 takes place, this inner barrel being formed of the inner tubular member 43 and the sleeve 45. The sleeve 45 provides an opening which is of substantially the same diameter as the internal diameter of the inner tubular member 43 and which cooperates therewith to provide a core chamber 48, the lower end of which communicates with a bore 49 of a cutter 50 which 20 may be threaded to the lower end of the body 32 and which is adapted to loosen the material which is to rise in the core chamber. This cutter may be of any suitable design 25 and is supplied with mud through passages 51 formed through the body 32 and communicating with the annular space between the inner and outer tubular members. The mud is supplied to the interior of the drill pipe 10 through the customary swivel 52 and hose 35 53, this mud passing downward through the spider 36 and through holes 54 formed through the head 23.

It should thus be apparent that the inner barrel 46 is adjustably supported by the drill 40 pipe 10, and that during the lowering of the core barrel 15 into the well, the weight of the outer barrel 35 is supported on the guide blocks 27 which at this time rest in the lower 45 ends of their respective pockets 25. As soon as the cutter 50 hits a supporting surface, such as the bottom of the well, its downward motion is arrested, but the inner barrel 46 moves downward a slight distance relative thereto until the blocks 27 move into the upper 50 portions of their respective pockets.

Any rotation of the drill pipe 10 is, of course, transmitted to the outer barrel through the guide blocks 27, and after the core chamber has been partially or wholly 55 filled with a core sample, the drill pipe 10 is raised. The first upward movement thereof tends to move the inner barrel 46 upward relative to the outer barrel 35, this relative movement being arrested when the guide blocks 27 lie in the lower portion of their respective pockets 25 after which both the inner and outer barrels are moved upward in the well as a unit.

This relative movement between the inner 60 and outer barrels I utilize in moving one or

more jaws 60 into the core chamber 48 in clamping relationship with the lower portion of the core sample therein. Various linkages may be utilized for connecting the jaws to the inner and outer barrels, and the jaws may be mounted on either the inner or outer barrels without departing from the broadest concept of this invention. However, I prefer to pivotally mount the jaws 60 in openings 70 75 formed through the sleeve 45, these openings being of a shape corresponding to the contour of the jaws 60, as best shown in Figs. 2 and 6.

Any number of these jaw members may be utilized, but I prefer to use four of these 80 elements equally spaced around the sleeve 45. The shape of these elements is best shown in Fig. 7, each jaw being provided with a body 65 having a neck 67 extending upward therefrom.

Formed on this neck are sideward extending pivot pins 68 which are circular in cross-section and which are journaled in semi-circular channels formed in the sleeve 45. These pins are held in these semi-circular channels 90 by means of a plate 69, legs 70 of which have semi-circular channels therein which cooperate with the semi-circular channels of the sleeve 45 in journaling the jaws 60 on the pivot pins 68, the legs 70 extending downward on each side of the neck 67, as best shown in Fig. 4. The inner faces of the plate 69 are curved to correspond in contour to the curvature of the core chamber 48 and are held in pockets formed in the sleeve 45 by 100 screws 71.

Jaw faces 73 of the jaws 60 may be similarly curved, although in Fig. 7 such a curvature is not shown. The lower portion of these 105 jaw faces may be provided with teeth such as indicated by the numeral 74.

Extending upward from the neck 67 and into a chamber 75 formed in the sleeve 45 is a tongue 76, the chamber 75 containing a spring 77 compressed between the rear wall thereof and the tongue 76 so as to resiliently move the jaws 60 out of the core chamber 48 and into an annular cavity 80 formed in the core-catching body 32. This cavity is defined by an upward diverging surface 81 and an upwardly converging surface 82, the former being shaped to conform to the rear surface 83 of the jaws 60. The surface 82 provides a shoulder 84 which contacts an angled surface 85 of each of the jaws 60 when the inner barrel 46 is moved upward relative to the outer barrel 35.

Due to this engagement the jaws 60 are forced into the core chamber 48 against the action of their respective springs and into 120 positions shown by dotted lines 88 of Fig. 4. Such a relative upward movement of the inner barrel takes place when the drill pipe 10 is first moved upward, and the inward movement of the jaws 60 firmly clamps the 125

core retained in the core chamber at this time.

It should be understood that the inward force on the jaws 60 is exerted by the weight of the outer barrel 35, the turning-moment of each jaw due to this force being greater than the turning-moment due to the springs 77. However, should the core occupying the core chamber 48 be extremely hard, the jaws 60 may not move into their extreme inward position indicated by the dotted lines 88 of Fig. 4, but may be held in an intermediate position. No harm will result, for the pivot structure holding the jaws to the sleeve 45 is sufficiently strong to resist the forces thus set up, it being clear that if the jaws do not move into their dotted line position shown in Fig. 4, the guide block 27 will not be effective in supporting the weight of the outer barrel 35.

While I have shown and described the jaws 60 as being pivoted to the sleeve 45, it should be understood that my invention is not limited to this feature. These jaws may be slidably mounted in the sleeve, or may be formed of resilient material secured to the sleeve at their upper ends and tending to normally assume a retracted position in the annular cavity 80. Furthermore, it is not necessary to make the sleeve separate from the inner tubular member 43, this construction being utilized only for the sake of simplicity.

The relative position of the inner and outer barrels may be adjusted by turning the nut 39, thus raising or lowering the inner barrel relative to the outer barrel and thus changing the position of the jaws 60 relative to the core chamber 48. It is not necessary that the angular relationship between the inner and outer barrels be accurately fixed for the provision of the annular cavity 80 permits the jaws 60 to be positioned therein in any desired angular relationship.

Due to the fact that the jaws 60 are entirely withdrawn from the core chamber 48 when in retracted position, no projections are present hindering the upward passage of the core in the chamber.

The quick and positive gripping action exerted by the jaws 60 due to a relative movement of the inner and outer barrels is a very important part of this invention and is not necessarily predicated upon the use of the particular embodiment shown in the drawings, inasmuch as various means for accomplishing this end will be apparent to those skilled in the art.

I claim as my invention:

1. In combination in a core barrel for taking a core from a bore hole: walls forming a core chamber; hinged vertically hanging jaws mounted adjacent said core chamber in a manner to be movable thereinto; and means for withdrawing said jaws from said chamber when said core barrel is lowered into contact with the bottom of said bore hole and for moving said hinged vertically hanging jaws

into said chamber when said core barrel is raised from said bottom of said bore hole.

2. In combination in a core barrel: an inner barrel providing a core chamber open at its lower end; jaws carried by the lower portion of said inner barrel and movable into and from said core chamber; means for supporting said inner barrel; an outer barrel longitudinally slidably relative to said inner barrel between fixed limits, said outer barrel extending below the lower surface of said inner barrel and being in a lower position when said means is supporting said core barrel but being movable into an upper position when said outer barrel engages a supporting surface; and means on said outer barrel engaging said jaws during the movement of said outer barrel from an upper position into a lower position for moving said jaws into said core chamber.

3. In combination in a core barrel: an inner barrel providing a core chamber open at its lower end; jaws carried by the lower portion of said inner barrel and movable into said core chamber, said jaws being resiliently held in a retracted position in which they are substantially removed from said chamber; means for supporting said inner barrel; an outer barrel longitudinally slidably relative to said inner barrel between fixed limits, said outer barrel extending below the lower surface of said inner barrel and being in a lower position when said means is supporting said core barrel but being movable into an upper position when said outer barrel engages a supporting surface; and means on said outer barrel engaging said jaws during the movement of said outer barrel from an upper position into a lower position for moving said jaws into said core chamber.

4. A combination as defined in claim 2 in which said jaws are pivotally mounted relative to said inner barrel, and including spring means for retaining said jaws in a retracted position substantially removed from said chamber.

5. A combination as defined in claim 2 including a cutter mounted on said outer barrel.

6. In combination in a core taking device, inner and outer barrels, said inner barrel providing a core chamber open at its lower end, jaws hanging from hinges attached to the inner barrel and movable into said core chamber by means of the weight of the outer barrel.

7. In combination in a core taking device, inner and outer barrels, said inner barrel slidably mounted within said outer barrel, jaws hanging from hinges attached to the inner barrel, means for moving the jaws inwardly, said means actuated by the weight of said outer barrel.

8. In combination in a core taking device, inner and outer barrels, said inner barrel

providing a core chamber open at its lower end, jaws hanging from hinges attached to the lower portion of said inner barrel and movable into said core chamber.

5 9. In combination in a core taking device, inner and outer barrels, said inner barrel providing a core chamber open at its lower end, jaws hanging from hinges attached to the lower portion of said inner barrel and movable into said core chamber and adjustable means whereby the relative position of the barrels one to the other is controlled.

10 10. In combination in a core taking device, inner and outer barrels, said inner barrel providing a core chamber open at its lower end, jaws hanging from hinges attached to the lower portion of said inner barrel, adjustable means whereby the extent of movement of said jaws is controlled.

15 11. In combination in a core taking device, inner and outer barrels concentrically mounted, jaws hanging vertically from hinges attached to said inner barrel and means whereby said jaws may be turned toward the longitudinal axis of the barrels.

20 12. In combination in a core taking device inner and outer barrels concentrically mounted jaws hanging vertically from hinges attached to said inner barrel, springs to normally retain said jaws in position and means whereby the jaws may be turned toward the longitudinal axis of said barrels.

25 13. A core taking device comprising inner and outer barrels, slidably mounted one within the other, adjustable means whereby the relative position of the barrels may be controlled, vertically hanging jaws attached to the lower portion of said inner barrel, a cutter attached to the lower portion of said outer barrel and means whereby the weight of the outer tube actuates said jaws to move inwardly toward the longitudinal axis of said barrels.

30 In testimony whereof, I have hereunto set my hand at Los Angeles, California, this 31st day of May, 1929.
